COMBINED COASTER AND ASHTRAY

Louis Marsh, 752 Washburn St., West Englewood, N.J.

Filed May 10, 1960, Ser. No. 60,523

Term of patent 14 years

(Cl. D44—10)

FIG. 1.

FIG. 2.

FIG. 3.

FIG. 4.

Fig. 1 is a top plan view of a combination coaster and ashtray incorporating my novel design;

Fig. 2 is a side elevational view thereof;

Fig. 3 is a sectional view thereof, taken on the line 3—3 of Fig. 1; and

Fig. 4 is a bottom plan view thereof.

I claim:

The ornamental design for a combined coaster and ashtray, as shown.
